US00D819438S

(12) **United States Design Patent** (10) **Patent No.:** **US D819,438 S**
(45) **Date of Patent:** **** Jun. 5, 2018**

(54) **PACKAGE**

(71) Applicant: **BRAGI GmbH**, München (DE)
(72) Inventors: **Matthias Lackus**, München (DE);
Nikolaj Hviid, München (DE); **Arne D Loermann**, München (DE)
(73) Assignee: **BRAGI GmbH**, München (DE)
(**) Term: **15 Years**
(21) Appl. No.: **29/560,528**
(22) Filed: **Apr. 7, 2016**
(51) LOC (11) Cl. 09-03
(52) U.S. Cl.
USPC **D9/418**
(58) **Field of Classification Search**

(57) **CLAIM**

The ornamental design for a package, as shown and described.

DESCRIPTION

FIG. 1 is an exploded perspective view of a package shown in accordance with the present invention;

FIG. 2 is a front perspective view of FIG. 1 completely assembled;

FIG. 3 is a front view of FIG. 2;

FIG. 4 is a left side view thereof;

FIG. 5 is a right side view thereof;

FIG. 6 is a top view thereof;

FIG. 7 is a bottom view thereof;

FIG. 8 is a front perspective view of the package, partially assembled with environment;

FIG. 9 is a front open view thereof;

FIG. 10 is another front open view thereof;

FIG. 11 is another front open view thereof;

FIG. 12 is another front open view thereof;

FIG. 13 is another front open view thereof;

FIG. 14 is another front open view thereof;

FIG. 15 is another front open view thereof; and,

FIG. 16 is another front open view thereof.

In the drawings, the broken lines are for the purpose of illustrating environment only and form no part of the claimed design.

1 Claim, 14 Drawing Sheets
